UNITED STATES PATENT OFFICE.

AUGUSTUS L. MOSS, OF SANDUSKY, OHIO.

SANDING DEVICE.

No. 802,230.

Specification of Letters Patent.

Patented Oct. 17, 1905.

Application filed February 17, 1905, Serial No. 246,035.

To all whom it may concern:

Be it known that I, AUGUSTUS LEICESTER Moss, a citizen of the United States, and a resident of Sandusky, in the county of Erie and 5 State of Ohio, have invented a new and Improved Sanding Device, of which the following is a full, clear, and exact description.

The object of the invention is to provide a new and improved sanding device, more especially designed for use on automobiles and like vehicles and arranged to permit the chauffeur to throw the sanding device quickly into action to sprinkle the road-bed with sand whenever required with a view to prevent the vehicle-wheels from slipping, especially when 15 the road-bed is wet or otherwise rendered slippery.

The invention consists of novel features and parts and combinations of the same, as 20 will be more fully described hereinafter and then pointed out in the claims.

A practical embodiment of the invention is represented in the accompanying drawings, forming a part of this specification, in which 25 similar characters of reference indicate corresponding parts in all the views.

Figure 1 is a plan view of the improvement as applied to an automobile, part of the automobile-body being broken out. Fig. 2 is an 30 enlarged sectional side elevation of the same on the line 22 of Fig. 1. Fig. 3 is a sectional plan view of the sand-distributer, and Fig. 4 is a like view of a modified form of sand-distributer.

35 On the frame or body A of the automobile or other vehicle is secured a sand-box B for containing sand adapted to pass from the sand-box through a feed-chute C onto the top of a horizontally-disposed revolving distributer D in the form of a disk having radially-disposed 40 guide-ribs D' to cause the sand to be forced from the disk by centrifugal force, the ribs D' guiding the sand in its discharge from the disk, so that the sand is scattered over the 45 road-bed mainly in front and in back of the driven wheels A' of the vehicle to allow forward or backward running of the vehicle on a wet or otherwise slippery road-bed, it being understood that the scattered sand provides 50 sufficient friction on the slippery road-bed to prevent the wheels from slipping. In order to prevent the sand from moving upward on the distributer D, the top thereof is covered by a disk C, fixed on the lower end of the 55 feed-chute C, as plainly illustrated in the drawings.

The guide-ribs D are preferably disposed radially and may be of the same or alternately of different lengths, as will be readily understood by reference to Figs. 3 and 4. By having the guide-ribs alternately of different lengths the sand is scattered over a greater area on the road-bed to thoroughly sand the same for the wheels A' to obtain a good hold with a view to prevent the wheels from slipping no matter in what direction the automobile is propelled at the time.

The disk of the distributer D is secured on a centrally-disposed shaft D², extending upward through the feed-chute C and journaled 70 at its upper end in the top of the chute, which forms a fixture of the sand-box B, but may be otherwise arranged. On the upper end of the shaft D² is secured a bevel gear-wheel E, in mesh with a bevel gear-wheel E', fastened 75 on one end of the shaft F' of a feed-screw F, mounted to turn in the bottom of the sand-box B, so as to feed the sand from the sand-box B positively into the chute C, from which the sand drops by its own gravity centrally 80 onto the disk of the distributer D to be expelled from the latter by centrifugal force when the disk D is rotated.

On the shaft F' of the feed-screw F is secured a sprocket-wheel G, over which passes 85 a sprocket-chain G', also passing over a sprocket-wheel G², mounted to rotate loosely on the drive-shaft H of the automobile or other vehicle. The sprocket-wheel G² is adapted to be connected by a clutch I of any 90 approved construction with the drive-shaft H, so that when the latter is rotated and the vehicle is propelled forward then the said clutch I rotates with the drive-shaft H and turns the sprocket-wheel G² to rotate the 95 feed-screw F, which in turn rotates the disk D by the gearing above described. Normally, however, the clutch I is out of engagement with the sprocket-wheel G² and is adapted to be thrown into engagement with the 100 said sprocket-wheel whenever it is desired to sand the roadway, as previously explained. For the purpose mentioned the clutch I is engaged by a shifting-lever J, connected by a link K with a lever L, having a foot-piece L' 105 within reach of the foot of the chauffeur or other operator, the lever L being pressed on by a spring N to normally hold the same in a rearward position and the clutch I out of engagement with the sprocket-wheel G². When 110 the operator presses the foot-piece L' forwardly against the tension of the spring N,

then the link K imparts a swinging motion to the shifting-lever J to shift the clutch I in engagement with the sprocket-wheel G² for rotating the feed-screw F and the disk of the distributor D in unison for the feed-screw to feed the sand to the chute C and for the distributor to scatter the sand onto the roadway with a view to prevent slipping of the wheels A'. As soon as the operator releases the pressure on the foot-piece L' the clutch I is thrown out of mesh with the sprocket-wheel G², so that the rotary motion of the latter, and consequently that of the feed-screw F and the distributor D, ceases.

15 The device is very simple and durable in construction, can be readily applied to automobiles and similar vehicles as now constructed, and is completely under the control of the chauffeur to permit the latter to actuate the device with a view to sand the road-bed whenever it is desired to do so.

Having thus described my invention, I claim as new and desire to secure by Letters Patent—

1. A sanding device for automobiles and like vehicles, provided with a revoluble distributor connected with a sand-supply and adapted to scatter the sand on the road-bed by centrifugal force.

2. A sanding device for automobiles and like vehicles, provided with a revoluble distributor connected with a sand-supply and adapted to scatter the sand on the road-bed by centrifugal force, the distributor being disposed horizontally and provided with ribs for scattering the sand.

3. A sanding device for automobiles and like vehicles, comprising a sand-box, a horizontally-disposed revoluble distributor adapted to scatter the sand on the road-bed by centrifugal force, a feeding device for feeding the sand from the said sand-box to the center of the said distributor, and a driving means for rotating the distributor from a driven part of the vehicle.

45 4. A sanding device for automobiles and like vehicles, comprising a sand-box, a horizontally-disposed revoluble distributor adapted to scatter the sand on the road-bed by centrifugal force, a feeding device for feeding the sand from the said sand-box to the center of the said

distributer, a driving means for rotating the distributer from a driven part of the vehicle, and a stopping and starting device under the control of the operator, for connecting and disconnecting the said driving means and the said distributor.

5 5. A sanding device for automobiles and like vehicles, comprising a sand-box, a revoluble disk disposed horizontally and having ribs on its upper face, and a feed-chute connected with the said sand-box and discharging onto the said upper face of the disk.

6 6. A sanding device for automobiles and like vehicles, comprising a sand-box, a revoluble disk disposed horizontally and having ribs on its upper face, the said ribs being alternately of different length, and a feed-chute connected with the said sand-box and discharging onto the said upper face of the disk.

7 7. A sanding device for automobiles and like vehicles, comprising a sand-box, a feed-chute leading therefrom, a horizontally-disposed distributing-disk having guide-ribs on its upper face and on which discharges the said feed-chute, a feed-screw in the said sand-box, for feeding the sand from the said sand-box into the said feed-chute, a gearing for rotating the said feed-screw and disk in unison, and a driving device for driving the said feed-screw from a driven part of the vehicle.

8 8. A sanding device for automobiles and like vehicles, comprising a sand-box, a feed-chute leading therefrom, a horizontally-disposed distributing-disk having guide-ribs on its upper face and on which discharges the said feed-chute, a feed-screw in the said sand-box, for feeding the sand from the said sand-box into the said feed-chute, a gearing for rotating the said feed-screw and disk in unison, a driving device for driving the said feed-screw from a driven part of the vehicle, and manually-controlled means for throwing the feed-screw in or out of gear with the said driven part.

In testimony whereof I have signed my name to this specification in the presence of two subscribing witnesses.

AUGUSTUS L. MOSS.
